Patented Dec. 14, 1915.

Inventor

JOSEPH FRANCIS

By Watson E. Coleman

Attorney

UNITED STATES PATENT OFFICE.

JOSEPH FRANCIS, OF WAPANUCKA, OKLAHOMA.

FOLDING BOX.

1,163,652.

Specification of Letters Patent. Patented Dec. 14, 1915.

Application filed September 1, 1915. Serial No. 48,552.

To all whom it may concern:

Be it known that I, JOSEPH FRANCIS, a citizen of the United States, residing at Wapanucka, in the county of Johnston and State of Oklahoma, have invented certain new and useful Improvements in Folding Boxes, of which the following is a specification, reference being had to the accompanying drawings.

10 This invention relates to certain new and useful improvements in folding boxes or shipping crates and has for its primary object to provide a box structure, the several elements of which may be readily assembled or disassembled and, in their latter condition, compactly arranged so that they will occupy a minimum of space in transportation.

20 The invention has for one of its more important detail objects the provision of a novel connecting means between the top and bottom sections of the box, whereby the side and end sections will be properly held in their erect positions when the box is 25 set up.

It is a further general object of the invention to provide a folding or collapsible box which is simple and durable in its construction, highly serviceable and convenient in 30 practical use and capable of manufacture at relatively small cost.

With the above and other objects in view, my invention consists in the novel features of construction, combination and arrangement of parts to be hereinafter more fully described, claimed and illustrated in the accompanying drawing, in which,

Figure 1 is a vertical longitudinal sectional view through a folding box constructed in accordance with the preferred embodiment of my invention; Fig. 2 is a section taken on the line 2—2 of Fig. 1; Fig. 3 is a longitudinal sectional view of the box collapsed; and Fig. 4 is an end elevation.

45 Referring in detail to the drawing, 5 designates the bottom or base section of the box, 6 the top thereof, and 7 the two end sections which are connected at their lower edges to the bottom 5 by means of hinges 8. The vertical edges of the end sections 7 are rabbeted, as at 9.

10 indicates the side sections of the box which, when in assembled position, rest 55 upon the longitudinal edges of the bottom 5 inwardly of the upstanding cleats or flanges

5' secured upon said bottom section. Each of these side wall sections of the box is also rabbeted or recessed at its opposite ends to provide the shoulders 11 thereon which fit 60 within the rabbeted vertical edges 9 of the end sections of the box.

12 indicates a partition or division wall which is connected by hinges 13 to the inner face of one of the side wall sections 10. 65

To each end of the top and bottom sections of the box, spaced I-bolts 14 are secured, and to the same, the ends of rods 15 are loosely connected. These rods, at their opposite ends, are integrally formed with or rigidly 70 connected to a ring 16, and through one of the rings, an elongated link 17 is engaged. A latch element 18 is loosely connected to one end of the link 17 and is formed adjacent to the link with a bend or seat 19. The 75 free end of the latch element is reversely extended and, after being engaged through the other of the rings 16, extends along one side of the link 17 in parallel relation thereto. Upon this side of the link, a clamping ring 20 is loosely engaged and is adapted to be slipped over the free end portion of the latch element whereby the same is held in connection with the link, as clearly shown 80 in Fig. 4 of the drawing.

In the operation of my invention, it will be understood that, when it is desired to collapse the box, the locking ring 20 is slipped upwardly upon the link 17 so that the latch element 18 can be disconnected from the ring 16 and the top 6 of the box removed. The ends 7 of the box are then folded inwardly 85

upon the bottom, as indicated in dotted lines in Fig. 1, and the two side sections 10 are removed, the partition 12 being folded upon the inner face of one of the side walls. These side sections are then arranged upon the two end sections of the box and the top section finally placed upon the side sections. Thus, the several parts of the box structure 90

will be compactly arranged as shown in Fig. 3, and bolts, ropes or other suitable connecting means may be passed through the eyes 14 on the ends of the top and bottom sections so as to hold the several parts against relative movement. When the box is set up in 95

position for use after being filled, the connecting means between the top and bottom sections of the box act to securely clamp the vertical side sections in place and hold the 100 same against outward movement, the end walls 7 of the box structure preventing any 105

longitudinal shifting of the side walls, as will be readily understood.

From the above description, taken in connection with the accompanying drawing, the construction, manner of operation and several advantages of my invention will be clearly and fully understood. The device, while of very simple construction, is highly serviceable in practical use, as it provides a collapsible box or crate for the shipment of commodities which may be very easily and quickly set up in condition for use or knocked down and the several elements thereof compactly arranged so that a large number of the boxes will occupy but a minimum of space in transportation. It is, of course, apparent that the boxes or crates can be made in various sizes and of any capacity.

While I have shown and described the preferred form and construction of the several parts, it is to be understood that the same are susceptible of considerable modification therein and I, therefore, reserve the privilege of resorting to all such legitimate changes as may be fairly embodied within the spirit and scope of the invention as claimed.

Having thus fully described my invention, what I desire to claim and secure by Letters Patent is:—

1. In a collapsible box, top and bottom sections provided with cleats on their longitudinal edges, removable side sections adapted to be fitted between the top and bottom sections against the inner faces of said cleats, end sections hinged upon the bottom section for folding movement, rods loosely connected to the ends of the top and bottom sections, elongated links connected to the rods on the

top section of the box, rings connected to the rods on the bottom section, latch elements permanently connected to said links for engagement through said rings, and locking rings having non-detachable sliding engagement upon said links and adapted for engagement with the respective latch elements to connect the top and bottom sections of the box and hold the same in clamping engagement upon the upper and lower edges of said side sections.

2. In a collapsible box, top and bottom sections, end sections hinged upon the bottom section and removable side sections, said end and side sections being adapted for arrangement in erect positions between the top and bottom sections, divergently disposed rods loosely connected to the opposite ends of the top and bottom sections, said rods being connected to each other by a ring, elongated links connected to the rings of the diverging rods which are connected to said top sections, a latch element carried by the link adapted to be engaged through the corresponding ring of the rods connected to the bottom section of the box, and a sliding locking ring on said link for engagement with the latch element to hold the same in connection with the latter, whereby the several sections of the box are securely held in assembled relation when the box is set up.

In testimony whereof I hereunto affix my signature in the presence of two witnesses.

JOSEPH FRANCIS.
